(57) **CLAIM**

The ornamental design for a bread lame as shown and described.

DESCRIPTION

FIG. 1 is a top perspective view of a bread lame showing my new design;

FIG. 2 is a bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof;

FIG. 9 is a top perspective view thereof, showing the bread lame parts in separated positions; and,

FIG. 10 is an enlarged view of a portion labeled as "10" on FIG. 1.

The dot-dash broken lines in the drawings illustrate the boundaries of the portions shown enlarged in the drawings and form no part of the claimed design.

1 Claim, 10 Drawing Sheets
